(57) **CLAIM**

The ornamental design for a hair curler, as shown and described.

DESCRIPTION

FIG. 1 is a top plan view of the hair curler.

FIG. 2 is a bottom plan view of the hair curler.

FIG. 3 is a right side elevational view of the hair curler.

FIG. 4 is a front elevational view of the hair curler.

FIG. 5 is a left side elevational view of the hair curler.

FIG. 6 is a rear elevational view of the hair curler.

FIG. 7 is a perspective view of a hair curler; and,

FIG. 8 is another perspective view of the hair curler.

The broken lines in the drawings illustrate portions of the hair curler that form no part of the claimed design.
